UNITED STATES PATENT OFFICE.

WILLIAM H. MEYER, OF ST. LOUIS, MISSOURI, ASSIGNEE, BY MESNE ASSIGNMENTS,
TO THE DAVIS SEWING MACHINE COMPANY, A CORPORATION OF DELAWARE.

DRAIN-PAN FOR CLOTHES-WRINGERS.

1,398,337.

Specification of Letters Patent. Patented Nov. 29, 1921.

Application filed February 7, 1920. Serial No. 357,054.

To all whom it may concern:

Be it known that I, WILLIAM HENRY MEYER, a citizen of the United States of America, a resident of the city of St. Louis, 5 in the State of Missouri, have invented certain new and useful Improvements in Drain-Pans for Clothes-Wringers, of which the following is a full, clear, and exact description, reference being had to the accompanying 10 drawings, forming a part of this specification.

This invention relates to improvements in drain pans for clothes wringers, the object being to provide a simple means whereby 15 the water passing from the wringer rolls may be selectively deflected to either side of the wringer. In the preferred form of the invention, a trough is located below the wringer rolls to receive the water passing 20 therefrom, said trough having an outlet for the water. A drain pan, located below the trough, comprises water deflectors in the form of chutes inclined downwardly from opposite sides of the wringer, each chute 25 having an inlet pocket or member adapted to register with the outlet of the trough. By shifting either the trough or the drain pan, the relative positions of the trough outlet and the inlet pockets may be changed to locate 30 either inlet pocket in registration with the trough outlet. I have herein shown a drain pan which may be shifted longitudinally of the trough to locate either inlet pocket in registration with the trough outlet, 35 thereby permitting drainage of the water to either side of the wringer. I have also shown a trough outlet comprising a series of discharge openings adapted to register with a row of inlet pockets in the drain pan.

With the foregoing and other objects in view, the invention comprises the novel construction, combination and arrangement of parts hereinafter more specifically described and illustrated in the accompanying drawings 45 wherein is shown the preferred embodiment of the invention. However, it is to be understood that the invention comprehends changes, variations and modifications which come within the scope of the 50 claims hereunto appended.

Figure I is a perspective view of a drain pan embodying the features of this invention.

Fig. II is a horizontal section, partly in

elevation, showing the trough from which 55 water is discharged to the drain pan.

Fig. III is a vertical section showing the drain pan, the trough, and the wringer rolls above the trough.

In Fig. III I have shown a portion of a 60 wringer frame A wherein wringer rolls B are mounted, and a trough C located directly below the wringer rolls, the upper margins of said trough being secured to the wringer frame. A drain pan D is located 65 below the trough to receive the water passing therefrom, the bottom of the trough being perforated to form a series of discharge members 1 for the discharge of water to the middle portion of the drain pan. The discharge members 1 are formed in a row arranged longitudinally of the trough.

To provide a simple means for supporting the drain pan, the lower margins of the wringer frame A may be turned inwardly, 75 as shown at 2 in Fig. III, and the side margins of the drain pan may be provided with hanger arms 3 having their upper ends extending outwardly so as to lie within the guideways formed by said margins 2. The 80 drain pan is thus slidably supported in the guideways 2 and it may be shifted longitudinally of the trough C for a purpose which will be hereinafter pointed out.

The drain pan comprises a pair of water 85 deflectors 4 and 4' in the form of chutes inclined downwardly from opposite sides of the wringer, a series of inlet pockets 5 in free communication with the chute 4, and a series of inlet pockets 5' communicating 90 with the chute 4'. These pockets are formed by a corrugated strip of metal 6 extending entirely across the middle portion of the drain pan. The inlet pockets of each series are thus formed in alternating relation to 95 the pockets of the other series. By referring to Fig. II it will be seen that the pockets 5' register with the outlet openings 1 in the bottom of the trough C, so the water dropping from the trough will fall into the 100 pockets 5' which are in free communication with the chute 4' leading from one side of the wringer. When the drain pan is positioned as shown in Fig. II, all of the water dropping from the trough will escape 105 through the pockets 5' and chute 4', for the corrugated strip of metal 6 will then prevent the water from reaching the chute 4.

However, as previously suggested, the drain pan can be shifted longitudinally of the trough to locate its pockets 5 in registration with the trough outlets 1, and the water passing from the trough will then flow into the pockets 5 from which it will escape by flowing down the chute 4. By merely shifting the drain pan, the operator can provide for the drainage of water to either side of the 10 wringer.

The chute 4' preferably includes a detachable extension 4^a secured by means of pivot bolts 7 passing through vertical flanges formed at the side margins of the drain pan 15 and its extension 4^a. When the drain pan is used with some types of washing machines, it is desirable to swing the extension 4^a to a position beyond the path of the washing machine tub, and this can be accomplished by 20 merely moving said extension on the axis of its pivots 7.

I claim:

1. A wringer provided with pressure rolls, a trough located below said rolls to receive 25 water passing therefrom, said trough having a water outlet, and a drain-pan below said trough, said drain-pan comprising water deflectors inclined downwardly from opposite sides of the wringer and inlet pockets communicating with the respective water deflectors, each of said inlet pockets being 30 adapted to register with said water outlet to receive the water flowing therefrom, and said drain pan being shiftable longitudinally of said trough to selectively locate either of said inlet pockets in registration 35 with said water outlet.

2. A wringer provided with pressure rolls, a trough located below said rolls to receive

the water passing therefrom, said trough 40 having a series of water outlets, and a drain pan below said trough, said drain pan comprising water deflectors in the form of chutes inclined downwardly from opposite sides of the wringer and two series of inlet pockets 45 between said chutes, the pockets of one series being in communication with one chute and the pockets of the other series being in communication with the other chute, each series of inlet pockets being adapted to register 50 with said series of outlets, and the drain pan being shiftable to selectively locate either series of inlet pockets in registration with said series of water outlets.

3. A wringer provided with pressure rolls, 55 a trough located below said rolls to receive the water passing therefrom, said trough having a series of water outlets, and a drain pan below said trough, said drain pan comprising water deflectors in the form of chutes 60 inclined downwardly from opposite sides of the wringer and two series of inlet pockets between said chutes, the pockets of one series being in communication with one chute and the pockets of the other series being in communication with the other chute, each series of inlet pockets being adapted to register 65 with said series of outlets, the pockets of each series being formed in alternating relation to the pockets of the other series, and 70 said drain pan being shiftable longitudinally of said trough to selectively locate either series of inlet pockets in registration with said series of water outlets.

In testimony that I claim the foregoing I 75 hereunto affix my signature.

WILLIAM H. MEYER.
